CONTROL PANEL FOR AN X-RAY APPARATUS

Vitislav Yakovlevich Bobov, Bolsheokhtinsky prospekt 12, kv. 42; Dmitry Petrovich Rybakov, ulitsa Dzerzhinskogo 69, kv. 22; and Avrum Lvovich Farberg, ulitsa Bolshaya Ozernaya 86, kv. 1, all of Leningrad, U.S.S.R.

Filed June 15, 1973, Ser. No 370,473

Term of patent 14 years

Int. Cl. D24—02; D13—03
U.S. Cl. D83—1 H

FIG. 1 is a front view of a control panel for an X-ray apparatus showing our new design;

FIG. 2 is a right side view, the opposite side being a mirror-image thereof;

FIG. 3 is a rear view;

FIG. 4 is a top plan view;

FIG. 5 is a bottom plan view; and

FIG. 6 is a perspective view of the control panel.

We claim:

The ornamental design for a control panel for an X-ray apparatus, as shown and described.
